APPARATUS FOR TREATING WITH LIQUID
RUNNING YARNS AND THREADSFrederick F. Sutherland and Donald K. Wilson,
Cumberland, Md., assignors to Celanese Corporation of America, a corporation of Delaware

Application July 31, 1945, Serial No. 608,007

7 Claims. (Cl. 91—32)

1
This invention relates to the treatment of running yarns and threads, and relates more particularly to novel apparatus for the application of liquid media to running yarns and threads in a uniform manner.

In the application of various liquid media to running yarns and threads, as during winding and twisting operations where the yarns and threads are traveling from bobbin to bobbin, not only must the liquid media be applied to the yarns and threads in a uniform manner but, in addition, any fly or throw of the liquid from the running yarns and threads must be kept to a minimum. An undesirable liquid throw is encountered particularly where a twist is being imparted to the yarns and threads simultaneously with the application of the liquid media. The ballooning of the yarn or thread in ring twisting operations, for example, results in a centrifugal force of a considerable degree causing small liquid droplets to fall in all directions. Where liquid media containing dyestuffs are being applied to running yarns and threads for the purpose of dyeing the yarns and threads, it is quite important that the yarns and threads are dyed to an absolutely uniform shade. Any variations in the degree of dyeing will be quite apparent when said dyed yarns and threads are woven into fabrics and faulty application of the dyestuff may even necessitate a complete redyeing of the fabric to attain a uniform shade.

Various means, such as, wicks, rollers, etc., are employed for the application of liquid media to running yarns and threads. While they are quite satisfactory in many instances, they have been found to be unsuitable for the application of liquid compositions where the compositions contain a fairly volatile solvent component, since the volatile solvent tends to evaporate rather rapidly from the wicks or rollers. Where the composition employed contains a dyestuff, the evaporation of the solvents leaves an undesirable concentration of dyestuff on the wicks or rollers, thus making the uniform coloration of said running yarns and threads practically impossible. The concentrated dyestuff produces very streaky dyeing. Suitable apparatus for the application of liquid media to running yarns and threads, both of which will hereinafter be referred to as yarns, in a controlled and uniform manner with a minimum of solvent evaporation has long been sought.

It is, therefore, an important object of this invention to provide an improved apparatus for the uniform application of liquids, and especially

2
liquid media containing a volatile component, in controlled amount, to yarns and threads while the latter are moving from one yarn package to another.

Another object of this invention is to provide an effective and inexpensive apparatus adapted for the application of liquid media to running yarns and threads whereby any losses of the liquid media due to evaporation are reduced and the liquid throw due to centrifugal forces acting on said yarns during winding and twisting operations are held to a minimum.

Other objects of this invention will appear from the following detailed description and the accompanying drawing.

In the drawing,

Fig. 1 is a perspective view, of our improved apparatus for the application of liquid media to running yarns and threads, broken away to show the yarn guides and the means for controlling the amount of liquid remaining on the yarns, and,

Fig. 2 is a detailed view in perspective of another embodiment of the liquid control or stripping means which may be employed in connection with our novel apparatus.

Referring now to the drawing, and more particularly to Fig. 1, there is shown a vessel, generally indicated by reference numeral 3, provided with a closely fitted cover 4, which is attached to the upper portion of vessel 3 by means of a hinge 5. Any desired liquid may be placed in vessel 3 for application to the yarns or threads undergoing treatment. The cover 4 may be raised and rotated freely on hinge 5, thus providing easy access to the mechanism inside, as for cleaning and the like.

The cover 4 is provided on one side with a slot 6 in which is set a slotted yarn guide 7 and oppositely disposed thereto is a second slot 8 fitted with a slotted yarn guide 9. Mounted in a suitable threaded opening in cover 4 at a point between yarn guides 7 and 9 is a threaded rod, generally indicated by reference numeral 10, which acts as a supporting member for the component parts of our novel apparatus. At the top of the portion of rod 10 extending above cover 4, rod 10 carries a pair of pigtail yarn guides 11 and 12, in line with slotted yarn guides 7 and 9, respectively, fixed to a collar 13 which is threaded on to rod 10 and maintained in the desired vertically spaced relation with respect to cover 4 by a lock nut 14. Rod 10 may be vertically adjusted with respect to cover 4 by being given any desired number of turns in the proper direction and is

held in vertically adjusted position by means of a nut 15.

Carried on rod 10 at a point above the normal liquid level in vessel 3 is the means, generally indicated by reference numeral 16, whereby the amount of liquid applied to the running yarns is controlled and any excess stripped off. The novel stripping means comprises a plate 17 mounted on rod 10 and held in the desired position thereon by lock nuts 18 and 19. Plate 17 has attached thereto plate 20 adapted to pivot horizontally about a bolt 21 passing through a laterally extending portion of plate 17 and through plate 20. Held on plates 17 and 20 by means of retainers 22 and 23 are strippers 24 and 25 formed of rubber or other soft and flexible material, the latter being held in abutting relationship under suitable pressure by means of a spring 26. Strip retainers 22 and 23, as well as strippers 24 and 25 are held in position by screws 27 and 28, respectively, which are threaded into plates 17 and 20.

Any desired liquid composition may be applied in the following manner to a running yarn employing our novel apparatus. Cover 4 is raised and the yarn to be treated, indicated by reference numeral 29 and which has first been passed through pigtail guide 11, is led through slot 6 into slotted yarn guide 7, threaded through a pigtail guide 30 integral with the base of rod 10, and then upward between strippers 24 and 25 mounted on plates 17 and 20. The latter are forced apart against the pressure of spring 26 to allow yarn 29 to be placed therein. The yarn is then passed up through slot 8 and yarn guide 9 and then out through pigtail guide 12. The winding operation is started, cover 4 is then dropped and pigtail guide 30 is thus set below the level of the liquid in vessel 3, as shown by the dot-dash line in Fig. 1. The passage of yarn 29 through submerged pigtail guide 30 thoroughly impregnates said yarn with the liquid composition employed. The action of spring 26, which maintains a constant pressure on strippers 24 and 25 between which the running yarn is passing, serves to remove any surplus liquid from the running yarn and the liquid thus stripped from yarn 29 falls back into the main body of the liquid in vessel 3. After the excess liquid is stripped from yarn 29, the latter passes upwardly through guide 8 and pigtail 12 and may then be directed to any further textile processing operation, such as, for example, winding and twisting.

The amount of liquid applied to yarn 29 may be controlled by the degree of pressure applied on the yarn by the strippers, i. e. by the spring pressure applied on the strippers. Thus, any desired amount of liquid may be applied to the yarn. In the case where the liquid composition being applied comprises a solution of a dyestuff, the latter is applied in an extremely uniform manner. The presence of cover 4 over the liquid in vessel 3 minimizes any evaporation from the main body of the liquid. Extreme uniformity of shade may be further obtained by employing a series of interconnected vessels 3 and continuously circulating the dye liquor therethrough as by means of a pump so that the maximum uniformity of dyebath composition will be maintained.

Where a lighter degree of pressure on the yarn is desired as it passes through the strippers, a modification of the pressure mechanism may be employed as shown in Fig. 2. In this embodiment of the liquid stripping means of our novel

apparatus, there is employed a plate 31 having a vertical arm 32 integral therewith, carrying a plate 33 pivotally mounted on arm 32 as by means of a pin 34. Plate 31 is provided with a slot 35 and held therein, as by a screw 36, is a stripper 37. In abutting relationship to stripper 37 is a second stripper 38 set in a slot 39 in plate 33 and held therein as by a screw 40. The stripping mechanism shown in Fig. 2 is provided with a threaded hole 41 by means of which said assembly may be maintained on rod 10. In this modification of our novel apparatus, only the weight of plate 33 acts to force stripper 38 against stripper 37, thus enabling only very light pressure to be applied to the running yarn where only a very light tension is desired.

It is to be understood that the foregoing detailed description is given merely by way of illustration and that many variations may be made therein without departing from the spirit of our invention.

Having described our invention, what we desire to secure by Letters Patent is:

1. Apparatus for the application of liquid media to running yarns and threads, comprising a vessel for containing a liquid, a rod operatively mounted with respect to said vessel, yarn guide means on said rod both inside and outside said vessel for guiding a running yarn along a controlled path through the vessel and the liquid contained therein and stripping means mounted on said rod within said vessel and in the path of said running yarn for stripping excess liquid from the wetted yarn.

2. Apparatus for the application of liquid media to running yarns and threads, comprising a vessel for containing a liquid, a rod operatively mounted with respect to said vessel, yarn guide means on said rod both inside and outside said vessel for guiding a running yarn along a controlled path through the vessel and the liquid contained therein and stripping means mounted on said rod within said vessel and in the path of said running yarn for stripping excess liquid from the wetted yarn, said stripping means comprising flexible members in abutting relationship and bearing on said running yarn for stripping excess liquid therefrom.

3. Apparatus for the application of liquid media to running yarns and threads, comprising a vessel for containing a liquid, a cover for said vessel including yarn entry and exit means, a rod mounted in said cover, yarn guide means on said rod both inside and outside said vessel for guiding a running yarn along a controlled path through the vessel and the liquid contained therein and stripping means mounted on said rod within said vessel and in the path of said running yarn for stripping excess liquid from the wetted yarn.

4. Apparatus for the application of liquid media to running yarns and threads, comprising a vessel for containing a liquid, a cover for said vessel including yarn entry and exit means, a rod mounted in said cover, yarn guide means on said rod both inside and outside said vessel for guiding a running yarn along a controlled path through the vessel and the liquid contained therein and stripping means mounted on said rod within said vessel and in the path of said running yarn, said stripping means comprising flexible members in abutting relation and bearing on said yarn for stripping excess liquid therefrom.

5. Apparatus for the application of liquid media to running yarns and threads, comprising a ves-

sel for containing a liquid, a cover for said vessel including yarn entry and exit means, a rod mounted in said cover, yarn guide means on said rod both inside and outside said vessel for guiding a running yarn along a controlled path through the vessel and the liquid contained therein and stripping means mounted on said rod within said vessel and in the path of said running yarn, said stripping means comprising a plate having a flexible member attached thereto, a second plate pivotally mounted on the first mentioned plate having a second flexible member attached thereto and means for maintaining said flexible members in abutting relation whereby excess liquid is stripped from the yarn passing therebetween.

6. Apparatus for the application of liquid media to running yarns and threads, comprising a vessel for containing a liquid, a cover for said vessel including yarn entry and exit means, a rod mounted in said cover, yarn guide means on said rod both inside and outside said vessel for guiding a running yarn along a controlled path through the vessel and the liquid contained therein and stripping means mounted on said rod within said vessel and in the path of said running yarn, said stripping means comprising a plate having a flexible member attached thereto, a second plate pivotally mounted on and above the horizontal plane of the first mentioned plate and having a second flexible member attached thereto, the weight of said second plate being such that said flexible members are maintained in abutting relation and excess liquid is stripped from the yarn passing therebetween.

7. Apparatus for the application of liquid media to running yarns and threads, comprising a vessel for containing a liquid, a cover for said vessel including yarn entry and exit means, a rod mounted in said cover, yarn guide means on said rod both inside and outside said vessel for guiding a running yarn along a controlled path through the vessel and the liquid contained therein and stripping means mounted on said rod within said vessel and in the path of said running yarn, said stripping means comprising a plate having a flexible member attached thereto, a second plate pivotally mounted on the first mentioned plate having a second flexible member attached thereto and spring means for maintaining said flexible members in abutting relation whereby excess liquid is stripped from the yarn passing therebetween.
